(57) **CLAIM**

We claim the ornamental design for a combination battery and case for electronic equipment, as shown and described.

DESCRIPTION

FIG. 1 is a front perspective view of a combination battery and case for electronic equipment, showing our new design; FIG. 2 is a rear perspective view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front elevational view thereof;

FIG. 8 is a rear elevational view thereof;

FIG. 9 is an exploded front perspective view thereof;

FIG. 10 is an exploded right-side elevational view thereof;

FIG. 11 is an exploded left-side elevational view thereof;

FIG. 12 is an exploded front elevational view thereof; and,

FIG. 13 is an exploded rear elevational view thereof.

The broken lines in the drawings depict environmental matter and form no part of the claimed design.
